CLAIM

The ornamental design for a docking station, as shown and described.

DESCRIPTION

FIG. 1 is a front perspective view of a docking station showing our new design;

FIG. 2 is a top view thereof;

FIG. 3 is a front view thereof;

FIG. 4 is a right side view thereof; and,

FIG. 5 is a left side view thereof.

The unshown rear and bottom with respect to FIGS. 1 through 5 form no part of the claimed design. The broken line showing of various regions in the Figures, including the unshaded areas therein, is for illustrative purposes only and forms no part of the claimed design.
